(57) **CLAIM**

The ornamental design for a pillow case with wings, as shown and described.

DESCRIPTION

FIG. 1 is a perspective top view of a pillow case with wings; FIG. 2 is a front elevation view of the pillow case with wings, rear elevation view being a mirror image thereof; FIG. 3 is a left side elevation view of the pillow case with wings; FIG. 4 the right side elevation view of the pillow case with wings; FIG. 5 is a top plan view of the pillow case with wings; and, FIG. 6 is a bottom plan view of the pillow case with wings. The stipple shading represents a contrasting surface appearance from what is shown on the opposite side.
